STAPLING MACHINE

Harold S. Heller, Cleveland Heights, Ohio

Application June 25, 1942, Serial No. 448,358

4 Claims. (Cl. 1—49)

This invention relates to staple driving machines, and more particularly to those which employ U-form wire staples, from the crown of which a portion is removed, so that the staple legs are driven and serve after the manner of small brads, tacks or nails.

One object of the invention is to provide an improved machine of this kind particularly designed for use with a U-form staple having its crown weakened in such manner that the machine itself, during the normal operation of driving the staple into the work, and without the use of extra staple shearing, cutting or deforming parts, accomplishes not only the driving of the two spaced staple legs but also removal of the excess metal of the crown between them.

A further object is to provide an improved stapling machine, the driving tool of which applies driving impact to a staple only at the upper ends of its legs, while the cross connecting crown piece maintains the legs in correct driving position, enabling them accurately to be driven endwise into the work, but finally leaving behind them the crown portion of the staple by severing it along weakened lines near to but spaced from the legs, to provide a head for each leg.

A further object is to provide an improved machine of this kind which is of simple construction; which may be used efficiently with standard staples as an ordinary tool; and which, when used with weakened wire staples, converts them in effect into headed brads and drives them to a depth sufficient to bury or countersink their heads in the work.

Further objects of the invention are in part obvious and in part will appear more in detail hereinafter.

In the drawing, which represents one suitable embodiment of the invention, Fig. 1 is a side elevation;

Fig. 2 is a detail sectional elevation on approximately the line 2—2, Fig. 1, looking in the direction of the arrows, and showing the driving tool ready to engage a staple for driving the same;

Fig. 3 is a similar view showing the staple partly driven;

Fig. 4 is a similar view, showing the parts in their positions just before the shearing operation begins;

Fig. 5 is a similar view, but illustrating only the work and staple, with the parts in their final positions;

Fig. 6 is a detail sectional plan view on the line 6—6, Fig. 3;

Fig. 7 is a perspective view, on a larger scale, illustrating one form of staple which may be used;

Fig. 8 is a similar view of another form of staple; and

Fig. 9 is a plan view of the finished work.

The invention now to be described is an improvement upon that shown, described and claimed in my prior application for Stapling machine, filed December 8, 1941, Serial No. 422,077, to which reference may be had if desirable or necessary. In said application the stapling machine operates upon standard U-form wire staples, being provided with a shearing anvil which cooperates with the driving tool to shear away a portion of the staple crown just before the heads of the remaining brad form staple legs are countersunk into the work.

According to the present invention, a special form of U-form staple is employed, made of a piece of wire of uniform cross section, having its crown portion cut, indented or otherwise weakened at two points near to but spaced from the legs in such manner that the end shoulders of the two arms of the staple driving tool come near to or register with said weakened portions and accomplish severance of the wire when the staple crown engages the face of the work. This reduces wear and tear on the machine parts, relieves them of some duty, dispenses with an extra anvil part, and nevertheless accomplishes the task efficiently and satisfactorily.

The operating parts of the stapling machine, in so far as they are designed to feed, guide and drive the staples, may be of any form suitable for the purpose. As shown, they comprise a hollow body or frame 1, within which the operating parts are housed or enclosed. The staple driving tool 2 moves in a channel or guideway 3, being operated by pressure or impact of the hand upon the head 4 of a plunger 5 biased upwardly by the usual compression spring 6. Staples are fed one by one to said channel ahead of the driving tool, said staples being advanced along a track or guideway 7 by a follower 8, as is usual.

Any suitable form of staple may be employed. The drawing shows a staple 10 of generally U-form made from a long length of wire of uniform rectangular cross section bent at two points 10a to form parallel legs 11 connected by a cross bridge or crown member 12, the arrangement presenting curved surfaces of the metal upwardly and outwardly at each of the bends 10a, where the legs join the crown. The latter is weakened

at two points 13, 14 fairly close to but yet spaced from the legs to enable the central portion of the bridge or crown readily to be removed during the driving operation, thus leaving behind it short end portions 15 which become the heads of the two brads formed by the legs. Weakening at the two points 13, 14 may be accomplished in any suitable manner, such as by grinding, cutting, indenting or the like and may take place either on one face of the wire alone, as in Fig. 8, or on opposite faces, as in Fig. 7.

These staples are usually supplied in the common gang form, with many thereof lying side by side in parallel relation and secured together by an adhesive. Weakening of the staples at 13, 14 may occur at any stage of manufacture thereof. Thus the staples may be formed individually from a long length of wire of the appropriate uniform cross section from end to end, with the weakening produced during the manufacture of each staple, e. g., by a grinding operation at the time of grinding the points, or, at least, before several staples are assembled and secured as a gang. If desired, wire may be cut and formed into staples which are assembled and secured as a gang by an adhesive, with the weakening operation performed while they are in gang relation, either before or after applying the adhesive, as will be readily understood.

The driving tool is of plate form fitting closely the channel in which it slides, its overall width and thickness corresponding to that of the staple crown member. But the intermediate portion of the working end of the tool is cut back or recessed, as at 16, to a depth slightly greater than the thickness of the staple wire and for a length equal to approximately the distance between the weakened points 13, 14. This recess provides the tool with two short side arm portions 17 provided with inner oppositely disposed shearing edge portions 18. Of course, the channel 3 ahead of the tool is free of obstructions all the way to the staple exit, which opens out through the tool nose at the bearing plate 19 which is applied to the work. This open channel permits free movement of the tool clear to the mouth of the channel whenever a staple is driven. Preferably, the leading or driving end edge portions of the two side arms 17 are each provided at their outer ends with a short projection, shown clearly at 30 in Figs. 2 and 4, said projections being curved to fit or match the curved surfaces at the bends 10a of the staple before referred to. During the driving operation these points or projections hug or embrace the staple and assist in driving its parts into the work without distortion at the bends between the crown and legs.

In use of the machine, it will be understood that it is loaded with a gang of staples secured to each other by adhesive, with the staples each of the form shown in either Fig. 8 or Fig. 9. The driving tool may be assumed to be in its upper or retracted position with the leading staple lying in the channel 3, ahead of the driver, with its legs extending toward the channel mouth, as shown in Fig. 2. With the parts so disposed the tool is applied directly to the work with one hand and pressure or impact of the other hand is applied to the plunger to drive the same down. This operation separates the first staple from the gang and carries it forward. It of course is confined by the walls of the channel 3, and between the projections 30 on the arms of the driving tool, but also the staple crown maintains

the staple legs in parallel relation and usually extending in a direction normal to the surface of the work. The two driving arms of the tool of course engage the staple only at the head ends of the staple legs and along the curved bends 10a referred to. The crown is left unsupported. As the plunger advances, the staple legs are driven endwise into and enter the work more and more, as shown in Fig. 3, until the parts reach the position shown in Fig. 4. Here the staple crown has reached contact with the face of the work, which is assumed to be wood or some material hard enough to prevent the full length of the crown from advancing further. However, pressure is still being applied by the tool arms to the upper ends of the staple legs and to the end portions of the staple crown lying outside of the weakened points 13, 14, with which the shearing edges 18 of the tool feet register. The consequence is that further pressure advances the tool still further, severing the wire by cutting or breaking at the weakened points 13, 14 and driving the small heads into the work to their final position, shown in Fig. 5, but without distortion. During the entire operation there is no likelihood of the staple legs bending or tilting toward or away from each other, because at first they are connected by the crown piece and later they are confined and supported by the work. The severed crown usually falls out of or may be removed from the tool as the parts return to their original positions ready for another operation.

The machine is frequently used for tacking molding to wood screen frames, such as the molding 20 to the frame 21. To more accurately register tool and work, the bearing plate 19 of the tool nose, through which channel 3 extends to its mouth, may be grooved laterally as at 24, to provide a shoulder for direct application to the molding with the latter in a position in registry with the mouth of said channel. In such case, if the stapling operation is performed at intervals along the molding, the final product presents the appearance of a series of brads or nails neatly distributed in recurring groups of two each.

It should be observed that recessing of the driving end of the tool for use with these weakened staples in the manner described does not interfere with use of the stapler in the usual way. It may be filled or supplied with ordinary unweakened wire staples of the same U-form shown in the drawing. So operated, the staples may be driven without severance of the central crown portions or countersinking thereof into the work, as will be readily understood.

The machine shown may be used with ordinary staples as an ordinary stapler, but when operated with the special staples shown converts them into spaced headed nails or brads which are driven without fear of bending or distortion. Other advantages of the invention will be apparent to those skilled in the art.

What I claim is:

1. A stapling machine for use with U-form staples having the crown portion weakened at two points to provide a head for each leg and presenting curved surfaces upwardly and inwardly where the legs are joined to the heads, comprising a frame provided with a staple guiding channel having an open mouth adapted to be applied to the work, said channel being open and unobstructed across its full area from end to end, means for supplying staples one by one

to said channel, and a driving tool movable in said channel and having its leading edge portion recessed between its ends to provide two driving arms, one on either side of the recess, and having depending projections at the outer ends of said arms, to thereby conform the arms to the heads, the tool recess forming two edge portions located so as to engage the staple near to its weakened portions, whereby the staple crown at its ends is embraced by and held between said projections during the driving operation and the heads are severed from the crown when it engages the work and both the legs and heads may be driven into the work without distortion at the bend between them.

2. A stapling machine for use with U-form staples having the crown portion weakened at two points near to but spaced from the legs to provide a head for each leg, comprising a frame provided with a staple guiding channel having an open mouth adapted to be applied to the work, an operating plunger, a tool operated thereby and slideable back and forth in said channel, said channel being open and unobstructed across its full area from the driving end of the tool to said mouth, and means for supplying staples one by one to said channel to a point in advance of the driving tool when the latter is in retracted position, said driving tool being provided with two arms spaced apart on opposite sides of a recess and having edge portions located so as to engage the staple crown near to its weakened portions, to thereby sever the legs from the crown when it engages the work and drive the legs and their heads into the work.

3. A stapling machine for use with U-form staples, comprising a frame provided with a staple guiding channel having an open mouth adapted to be applied to the work, an operating plunger, a tool operated thereby and slideable back and forth in said channel, said channel being open and unobstructed across its full

area from the driving end of the tool to said mouth, and means for supplying staples one by one to said channel to a point in advance of the driving tool when the latter is in retracted position, that portion of the machine frame adjacent the channel mouth which engages the work having a shouldered groove extending parallel to the length of the said channel mouth with the shoulder of said groove parallel to and at one side of the crown of a staple being driven, to accurately locate the staple legs with reference to the shoulder of said groove and to space them apart lengthwise of the work.

4. A stapling machine for use with U-form staples having the crown portion weakened at two points near to but spaced from the legs to provide a head for each leg, comprising a frame provided with a staple guiding channel having an open mouth adapted to be applied to the work, an operating plunger, a tool operated thereby and slideable back and forth in said channel, said channel being open and unobstructed across its full area from the driving end of the tool to said mouth, and means for supplying staples one by one to said channel to a point in advance of the driving tool when the latter is in retracted position, said driving tool being provided with two arms spaced apart on opposite sides of a recess and having inner edge portions located so as to engage the staple crown near to its weakened portions, that portion of the machine frame adjacent the channel mouth which engages the work having a shouldered groove extending parallel to the length of the said channel mouth with the shoulder of said groove parallel to and offset from the length of the crown of a staple being driven, to thereby sever the legs from the crown when it engages the work and drive the legs and their heads into the work at two points accurately spaced from the shoulder of said groove and spaced apart lengthwise of the work.

HAROLD S. HELLER.
